UNITED STATES PATENT OFFICE

LOUIS V. ARONSON, OF NEWARK, NEW JERSEY, ASSIGNEE TO ART METAL WORKS, INC.,
OF NEWARK, NEW JERSEY, A CORPORATION OF NEW JERSEY

COMBINED SAFETY RAZOR AND SHARPENING DEVICE

Application filed February 21, 1931. Serial No. 517,382.

Among the objects of this invention are improved means for facilitating the sharpening of razor blades without necessitating removal from the razor; improved means for moving the razor blade from shaving position to honing position; improved means for sharpening a razor blade while clamped in position in the razor including provision of means for mounting the razor blade holding 5 means to facilitate its movement in the direction of its length for sharpening the edges when moved in contact with the usual guards; improved means including special honing and sharpening devices together with 10 means for moving them into or out of cooperative position with the razor blade; and means for moving guard members into and 15 out of cooperative position simultaneously with the movement of the honing or sharpening members out of and into operative position.

Other objects of the invention will appear from the following description taken in connection with two embodiments shown in the 20 accompanying drawings, in which

Fig. 1 is a transverse section on the line 1—1 of Fig. 2 of one embodiment of the invention;

Fig. 2 is a transverse section on the line 2—2 of Fig. 1;

Fig. 3 is a top view of the razor as shown in Fig. 1;

Fig. 4 is a section on the line 2—2 of Fig. 1 showing the razor supporting carriage in moved position during the operation of sharpening;

Fig. 5 is a section on the line 5—5 of Fig. 4;

Fig. 6 is an elevation looking at the end 40 of the razor head of a construction made in accordance with a second embodiment of the invention;

Fig. 7 is a side view of the razor head;

Fig. 8 is a top plan view of the razor as 45 shown in Fig. 6.

Fig. 9 is a section on the line 9—9 of Fig. 6;

Fig. 10 is a perspective view of a razor supporting carriage;

Fig. 11 is a transverse section on the line 50

11—11 of Fig. 9 with the parts in position for shaving;

Fig. 12 is a section on the same line as Fig. 11 with the parts in position for honing;

Fig. 13 is a cross section on the line 13— 55 13 of Fig. 9 with the parts in the same position as in Fig. 11;

Fig. 14 is a cross section on the same line as Fig. 13 with the parts in the same position as shown in Fig. 12; 60

Fig. 15 is a longitudinal section on the line 15—15 of Fig. 12;

Fig. 16 is a perspective view of the pivoted honing plates disassociated from the razor head; and 65

Fig. 17 is a perspective view of one of the pivoted guards disassociated from the razor head.

The embodiment shown in Figs. 1 to 5 includes a handle 1 which may have a screw 70 threaded connection with a member 2 secured in any suitable manner to the main frame 3 of the razor head, which may be of the general shape indicated in Figs. 2 and 4, and have formed integral therewith guards 75 4 and 5 constructed as shown to provide guard teeth. It is obvious, of course, that these guard teeth may be formed in any suitable manner and that as to certain aspects of the invention, the teeth may be omitted and a continuous guard member used instead.

The guards 4 and 5 may be disposed at right angles to the upper part 6 of the frame 80 3 to receive a guide-way 7, or the guide-way 7 may be made integral with or formed on the member 6 in any suitable manner. Slidable on the guideway 7 and retained therein by overhanging flanges on the guide-way is a slide plate 8 in which are secured spacer 85 studs 9 and 10 on which is supported the inner clamping member 11 to which is clamped a razor blade 12 by an outer clamping member or cap plate 13.

Threadedly engaging the spacer studs 9 and 10 and securing the inner clamping member 11 thereto, are alining pins 14 and 15 which extend through the razor blade 12 and the outer cap plate 13 and are provided 90 with screw driver engaging slots for facil- 100

- tating their connection with and disconnection from the spacers 9 and 10. The sides of the alining pins may be shaped as shown in Fig. 3 to conform to the slot in a razor blade of standard make, the blade functioning in this instance to lock the alining pins 14 and 15 in the position in which they clamp the inner clamping member 11 on the spacer studs 9 and 10.
- 10 The cap plate or outer clamping member 13 may be provided with a short screw threaded member 16 with which cooperates a threaded member 17 having an enlarged portion resting on the slide 8 which also acts as a spacer member and having a reduced portion projecting through a hole in the slide 8 and slots in the guide-way 7 and the upper part 6 of the frame 3. The free end of the member 17 may be provided with 20 a thumb wheel 18, as shown. By turning the thumb wheel 18 the cap plate may be drawn inwardly toward the inner clamping member to secure the razor blade and to move it against the guards 4 and 5 under any desired 25 pressure for cooperation with the guards during the operation of the sharpening, as shown in Figs. 4 and 5, or to permit the withdrawal of the edges of the razor blade into any desired suitable shaving position, as 30 shown in Fig. 1.
- The spacer stud 10, as shown in Fig. 2, may be provided with a recess into which projects the wedge-shaped end of a bolt 20 which has a threaded connection with a member 21 supported in the frame member 3 and which may be turned and advanced by means of a thumb wheel 22 into the position shown in Fig. 2 in which it locks the slide 8, the clamping members and the razor blade in the position in 40 which these parts occupy during shaving.
- By withdrawing the bolt 20 from the recess in the spacer stud 10 into the position shown in Fig. 4 the slide 8 and all the parts carried thereby are free to be moved back and forth 45 in the guide-way 7 whereby, when the edges of the blade are drawn against the guards as shown in Fig. 5, the lower faces of the opposite edges of the razor blade will be sharpened. The opposite faces of the edges of the 50 razor blade may be sharpened after the blade has been reversed in the clamping members and the parts are again brought into the position shown in Fig. 5. The pressure of the razor blade on the guards may be adjusted by 55 means of the thumb wheel 18.
- After the sharpening operation has been completed the slide 8 is brought into the position shown in Fig. 2 and is locked in this position by advancing the bolt 20, after which 60 the thumb wheel 18 may be turned to space the edges of the razor blade from the guards 4 and 5, as shown in Fig. 1.
- The modification shown in Figs. 6 to 17 includes a handle 21 which has a reduced portion 22 adjustable in a member 23 secured to the frame member 24 of the razor head in any suitable manner.
- Formed integral with the frame member 24 are ears 25 and 26, and 27 and 28, in which are mounted rods 29 and 30 which support 70 movable guard members 31 and 32 provided with manipulative finger pieces 33 and 34 and arms 35 and 36 for raising the corresponding honing members 37 and 38 from the position shown in Figs. 11 and 13 to the position 75 shown in Figs. 12 and 14 as the guard members are moved out of shaving position. The construction is such also that when the guard members are moved into the shaving position shown in Figs. 11 and 13 they may cause the 80 honing members to move into fully withdrawn position. The movement of the honing members from the honing position shown in Fig. 12 upon release by movement of the guard members into shaving position is initiated by a spring 39, Fig. 16, coiled about a rod 40 and having its ends bearing against the honing plates 37 and 38. The plates 37 and 38 are provided with eyes through which the rod 40 extends. The rod 40 is supported 85 in upstanding ears 41 and 42 on the frame 24. The guard members may be provided with cam-shaped raised portions 43 and 44 cooperating with the free ends of a plate spring 45 secured to the bottom face of the frame 90 member 24 to hold the guard members in either of the positions indicated in Figs. 11 and 12 and Figs. 13 and 14.
- For the purpose of slidably supporting the 100 razor blade and clamping mechanism on the frame member 24 a guide-way 46 may be secured to the frame member 24, the guide-way being formed as in the first modification and being adapted to receive and cooperate with the base 47 of a razor carriage 48, Fig. 10, the 105 ends of the base being recessed, as shown in Fig. 10, to avoid interference with the ears 41 and 42 on the frame 24. The carriage 48 may be provided with a razor blade supporting member 49 which constitutes the inner 110 clamping member for the razor blade 50. The ends of the plate or supporting member 49 may be provided with finger pieces 51 and 52 by means of which the carriage 48 may be slid back and forth in guide-way 46. The finger pieces 51 and 52 also constitute abutments for the ends of the razor blade 50 as clearly indicated in Figs. 9 and 15. The plate 49 may be provided with alining studs 53 and 54 which 115 pass through a slot or the equivalent in the blade 50 and are enlarged to form seats for the outer clamping plate or cap member 55 which is provided with bayonet slots for connection under the heads of studs 53 and 54, 120 as clearly indicated. The right hand end of the cap plate 55 is recessed to clear the ear 51. The base member 47 of the carriage is provided with a recess into which the end 56 of the reduced portion 22 of the handle 21 may 125

extend to lock the carriage 48 in the position shown in Fig. 9.

When the carriage 48 is in the position indicated in Fig. 9, and the guards and honing members are in the position shown in Figs. 11 and 13, the razor is in condition for a shaving operation. When it is desired to hone the razor the guards are swung away from the edges of the razor blades into the position shown in Figs. 12 and 14 which causes the honing members 37 and 38 to be moved into cooperative relation with the edges of the razor blade for honing, as shown in these figures. The end 56 of the reduced portion 22 of the handle 21 is withdrawn by a counter-clockwise rotation of the handle, into the position shown in Figs. 14 and 15, so that the carriage 48 and the parts carried thereby may be moved back and forth to cause the edges 20 of the razor blade to move back and forth longitudinally of the honing plates, as indicated by the position of the parts shown in Fig. 15. After the honing operation has been completed the carriage 48 is centered with respect 25 to the frame 24 and the end of the handle is advanced from the position shown in Fig. 15 to the position shown in Figs. 9 and 13 to lock the carriage 48 and the parts carried thereby in shaving position.

While the invention has been described with particular reference to the embodiments disclosed, it is obvious that the invention may take other forms or embodiments, and it is to be understood that the words used in the 35 claims are words of description and not of limitation.

What I claim is:

1. The combination in a razor, of a fixedly mounted combined guard and honing device, supporting means for a razor blade mounted for movement in the direction of the length of said device for honing operation, and means for holding said supporting means against movement with respect to said device for shaving operations.

2. The combination in a razor, of a honing device, a razor blade supporting means, means for supporting said device and said razor blade supporting means to permit of relative longitudinal movement, and means for locking said device and said razor blade supporting means against longitudinal movement.

3. The combination in a razor, of spaced honing members, clamping means for supporting a double-edged razor blade, means for moving said clamping means to simultaneously move the edges of the razor blade into and out of honing position with respect to said honing members, and means for supporting said clamping means and honing members for relative longitudinal movement.

4. The combination in a razor, of spaced combined guard and honing devices, clamping means for a razor blade, means for mov-

ing said clamping means to present the edges of the blade in honing or shaving position with respect to said combined guard and honing devices, and means for supporting said clamping means and honing devices for relative longitudinal movement.

5. The combination in a razor, of razor blade supporting means, a movable guard member, a separate movable honing device, and means for moving said guard member out of cooperative position with respect to a blade in said supporting means and simultaneously moving said honing member into cooperative position with respect to said blade.

6. The combination in a razor, a handle, means supporting a razor blade in fixed spaced relation with respect to said handle, a movable guard cooperating with each edge of a double-edged razor blade supported in said means, a movable honing device cooperating with each edge of said razor blade, and means for alternately moving said guards and honing devices into cooperative position with respect to the edges of said razor blades.

7. The combination in a razor, of a handle, a frame member to which said handle is secured and through which it projects, a honing device supported on said frame member, means for mounting a razor blade, a slidable connection between said mounting means and said frame, and means on said sliding connection adapted to be engaged by the end of said handle extending through said frame member for locking said razor clamping means against sliding movement with respect to said honing device.

8. The combination in a razor, of razor blade supporting means, a movable guard cooperating with each edge of a double-edged razor blade supported in said means, a movable honing device cooperating with each edge of said razor blade, means for alternately presenting said guards and honing devices into cooperative position with respect to the edges of said razor blade, and means for holding said honing devices and guards in their cooperative positions.

9. The combination in a razor, of a razor blade supporting means, a movable guard cooperating with each edge of a double-edged razor blade supported in said means, a movable honing device cooperating with each edge of said razor blade, means for alternately moving said guards and honing devices into cooperative position with respect to the edges of said razor blade, and means for holding said honing devices and guards in their cooperative and withdrawn positions.

10. The combination in a razor, of a razor blade supporting means, a movably mounted guard, a separate movably mounted honing device, and means on the guard for engaging and moving said honing device into cooperative position with respect to a blade supported in said supporting means upon movement of

said guard out of cooperative position with respect to said blade.

11. The combination in a safety razor, of spaced honing devices, a pair of clamping plates for securing a double-edged razor blade in position, the outer of said clamping plates being arcuate transversely with respect to the blade with its edges cooperating with the blade near its edges and the inner clamping plate being of a smaller width than the outer clamping plate, means supporting said clamping plates and honing devices for relative longitudinal movement, and means for moving said outer clamping plates to move the edges of the razor blade into contact with said honing devices.

In testimony whereof I have signed my name to this specification.

LOUIS V. ARONSON.
